UNITED STATES PATENT OFFICE.

JOSEPH M. SCHUTZ, OF MINNEAPOLIS, MINNESOTA.

FLOUR-DRESSING MACHINE.

SPECIFICATION forming part of Letters Patent No. 292,259, dated January 22, 1884.

Application filed May 25, 1883. (No model.)

To all whom it may concern:

Be it known that I, JOSEPH MARTIN SCHUTZ, a citizen of the United States, and a resident of Minneapolis, in the county of Hennepin, in the State of Minnesota, have invented certain new and useful Improvements in Perpendicular Flour-Dressing Machines, of which the following specification is a full, clear, and exact description, reference being also had to the accompanying drawings, in which—

Figure 1 is a central vertical section of the machine. Fig. 2 is a detached detail of a portion of the reel and beater frame, illustrating a variation in the construction. Fig. 3 is a perspective view of a section of the beater-frame arranged as in Fig. 2. Figs. 4 and 5 are enlarged details of the feed-distributing plate. Fig. 6 is a cross-sectional view on the line $x-x$ of Fig. 1. Fig. 7 is a plan view of the outside of the machine.

A is the outer casing or frame-work in which the mechanism is supported.

B is a step secured in a cross-piece, A', in the lower part of the frame A, in which a hollow sleeve, C, is supported. Upon the upper end of the sleeve C a "spider" or circular frame, D', is mounted, and attached to this spider D' is a ring, E', having an inwardly and downwardly inclining interior, as shown. Journaled in a cross-piece, A², on the upper part of the frame A is another sleeve, C², similar to and in line with the sleeve C, and having a spider or frame, D², (similar to the spider D') secured to its lower end.

E² is a ring attached to the under side of the rim of the spider D², and E³ E⁴ are two other rings at equal distances apart between the rings E' E², all the rings being connected to each other by half-round upright bars or ribs a, the rings E³ E⁴ inclining inward, like the ring E'. The ribs a are arranged at equal distances apart around the rings, as shown in Fig. 3. In the drawings twelve of these ribs are shown; but a greater or less number may be used. The rings E' E² E³ E⁴ and the ribs a thus form a circular perpendicular frame, over which a covering of bolting-cloth, c, will be stretched.

F' is a shaft passing loosely down through the sleeves C' C², and also through the step B', and is held at its lower end by another step,

B², and is provided with a belt-pulley, F², by which the shaft may be revolved. Upon the upper end of the shaft F' is a chain-pulley, F³, connected by an endless chain, F⁴, to a chain-pulley, F⁵, upon a small shaft, F⁶, upon top of the casing A. Connected to this chain-pulley F⁵, so as to revolve with it, is another chain-pulley, F⁷, connected by a chain, F⁸, to a chain-wheel, F⁹, fast upon the sleeve C² outside the casing A, as shown. The pulley F⁵ is smaller than the chain-pulley F³, and the chain-pulley F⁷ is smaller than the chain-pulley F⁹, so that when the shaft F' is revolved the spiders D' D² and the bolting-cloth-covered frame connecting them will also be revolved through the medium of the chain-pulleys in the same direction, but at greatly reduced speed. The shaft F' will be revolved at about two hundred revolutions per minute, and the bolting-cloth cylinder revolved at about twenty revolutions per minute.

Attached to the shaft F' at equal distances from the rings E' E² E³ E⁴ are spiders G' G² G³, having sheet-metal rings H' H² H³, attached to the outer ends of their arms parallel with and near the inner edges of the rings.

Branching outward from each of the rings H' H² H³, tangentially inclined, or nearly so, are upright beaters b, and secured to the bottoms of each of the rings H' H² H³ and to the bottoms of each separate set of the beaters b are plates or disks K' K² K³, the outer edges of the disks and the beaters b being flush with each other and projecting a short distance beyond the inner edges of the rings E' E² E³ E⁴, as shown in Fig. 1, and as indicated by the dotted-line circle in Fig. 6.

In Fig. 2 a slight variation is shown in the manner of arranging the beaters b and deflecting-rings E' E² E³, consisting in forming the rings H' H² H³ in one continuous cylinder, H⁴, and forming the plates K' K² K³ in rings K⁵ around the cylinder H⁴. The rings E' E² E³ E⁴ are formed with flat portions t, and the rings K⁵ provided with inclined scrapers v, (see Fig. 3,) which scrape the material off from the flat parts t. The action and results are the same in both arrangements, however. Above the upper ring, H⁴, is a disk, K⁴, similar to the other disks, K' K² K³, and attached to the shaft F', so as to revolve with it, and upon which

the material to be acted upon in the machine is fed through a spout, L. Over the outer edge of this disk K¹ a deflecting-ring, d, is secured, to cause the material as it flows over the 5 edge of the plate to fall downward and not be thrown outward by the centrifugal force. The construction of this deflecting-ring is more clearly shown in Figs. 4 and 5.

M is a spout leading from the space between 10 the casing A and revolving reel, to conduct the material which passes through the bolting-cloth from the machine, while a similar spout, N, conveys the tailings away from the machine.

This machine may be used to separate any 15 of the reduced or partially-reduced particles of grain during the process of milling, but is more particularly applicable to dressing flour, and the operation is as follows: The material is fed in through the spout L upon the plate 20 K¹, and is forced outward by the centrifugal force and turned downward by the deflecting-ring d, and falls down between the ring H¹ and upper section of ribs a, where it is caught by the beaters b and thrown outward against the 25 ribs a and bolting-cloth c. Many of the particles fine enough to pass through the cloth will be driven through by this action, while the remainder will be thrown back again by the revolving ribs against the beaters, and by 30 them again thrown outward against the ribs and bolting-cloth. The material that fails to pass through the cloth falls down upon the inclined ring E¹, and is by it shot inward and downward between the second ring, H², and the 35 next section of ribs a, where the same action takes place, and so on down through each section until all the particles fine enough to pass through the bolting-cloth will have been forced through it, while the coarse tailings only will 40 reach the exit-spout N. By forming the beaters b in short sections and interposing the inwardly-inclining rings E¹ E² E³ and disks K¹ K² K³ between each section of beaters, the material is prevented from falling downward a 45 longer distance than the length of any one section of the beaters. Consequently upon the stoppage of the machine the material in the machine will be caught by the outer edges of

the disks K¹ and held suspended thereon until the machine starts again, so that no waste occurs by unseparated material passing through the machine. 50

Perpendicular reels possess many advantages over horizontal reels; but as heretofore constructed great annoyance is caused by the 55 material that happens to be in the machine at the time it is stopped falling into the hopper with the tailings and being lost, or necessitating the shutting off the supply and running the machine until the material in the machine 60 is separated; but by my arrangement these objections are removed.

In the horizontal reel only that portion of the reel that for the time being is running below the center or shaft of the reel is in actual 65 use, while in horizontal reels all the cloth on all sides is in constant use; hence the capacity of the machine is greatly increased.

Having described my invention and set forth its merits, what I claim is— 70

1. In a perpendicular flour-dressing machine, the combination of a slowly-revolving bolting-reel provided with inwardly-inclined rings E¹ E² E³ and vertical internal ribs a a, and a rapidly-revolving beater moving in the 75 same direction as the bolting-reel, and provided with ring-sections H¹ H² H³, beater-blades b b, and horizontal disks K¹ K² K³, substantially as and for the purpose herein specified. 80

2. In a perpendicular flour-dressing machine, the combination of the revolving bolting-reel, constructed with the inwardly-inclined rings E¹ E² E³ and vertical ribs a a, the beater-shaft, the beater-rings H¹ H² H³ inclined beater-blades b b, and horizontal disks K¹ K² K³, substantially as and for the purpose herein specified. 85

In testimony whereof I have hereunto set my hand in presence of two subscribing witnesses. 90

JOSEPH M. SCHUTZ.
